CLAIM

The ornamental design for a syringe barrel, as shown and described.

DESCRIPTION

FIG. 1 is a front view of a syringe barrel showing the new design;

FIG. 2 is a rear view of FIG. 1;

FIG. 3 is a top view of FIG. 1;

FIG. 4 is a bottom view of FIG. 1;

FIG. 5 is a left side view of FIG. 1;

FIG. 6 is a right side view of FIG. 1;

FIG. 7 is an enlarged section of the right side view of FIG. 6;

FIG. 8 is a perspective view of FIG. 1;

FIG. 9 is a cross-sectional view of FIG. 1 taken along line 9—9 of FIG. 5;

FIG. 10 is a cross-sectional view of FIG. 1 taken along line 10—10 of FIG. 5; and,

FIG. 11 is a cross-sectional front view of the syringe barrel having a plunger rod engaged therewith.

The broken lines in FIG. 11 represent environment and are for illustrative purposes only and do not constitute part of the claimed design.
